UNITED STATES PATENT OFFICE.

J CLIFFORD SMITH, OF BELLFLOWER, CALIFORNIA.

BRAKE-OPERATING MECHANISM.

Application filed March 2, 1926. Serial No. 91,785.

This invention relates to brake operating mechanism and more particularly to brake operating mechanism for the brakes of calf wheels of well drilling rigs or similar mechanisms.

In well drilling rigs, the calf wheel is driven by an engine and is employed for lowering and raising tools in the well. These calf wheels are controlled by a band 10 brake operated from a lever and often, due to sudden reversal of the engine, an unexpected engagement of the clutch or a sudden releasing of the weight which is supported from the calf wheel, this lever will suddenly 15 shift with the result that a workman is many times injured thereby. The probability of such injury occurring will be realized when it is noted that it is necessary to have a workman in constant attendance upon the 20 lever during drilling operations.

A further object of the invention is to produce a device of this character which may be applied to the operating levers of 25 calf wheel brakes which are now in position upon the rig.

A further object of the invention is to provide adjustable means for controlling the position of the calf wheel brake with relation to the rim of the calf wheel.

These and other objects I attain by the construction shown in the accompanying drawings, wherein for the purpose of illustration is shown a preferred embodiment of 30 my invention and wherein:

Figure 1 is a side elevation showing brake operating mechanism constructed in accordance with my invention, the control pawl being indicated in normal position by solid lines;

Figure 2 is a plan view of the brake operating mechanism detached;

Figure 3 is a sectional view showing the manner of connecting the cable with the brake lever.

Referring now more particularly to the drawings, the numeral 10 generally designates the calf wheel of well drilling apparatus, the calf wheel being rotatably mounted and having secured thereto the usual drum

50 11 upon which the tool cable 12 is wound. The numeral 13 generally designates a flexible brake band co-operating with the rim of the calf wheel and having one end thereof secured to a rigid support 14 while the

55 opposite end thereof is secured to the crank 15 of a crank shaft 16 mounted in suitable

bearings 17 upon the support 14 or upon the floor of the derrick. One end of this shaft has rigidly secured thereto an operating lever 18. The crank shaft 16 and lever 18 are usually produced from a single bar of round metal bent in the proper form. It will be obvious that by oscillating the lever 18, the band 13 may be engaged with or disengaged from the periphery of the 60 65 calf wheel.

In order to limit the separation of the brake band 13 from the periphery of the drum, I provide a limiting element consisting of a rod or cable 19 rigidly secured at 70 one end to a suitable support 20 which passes about and is substantially co-extensive with the band 13. The opposite end of the limiting element 19 is adjustably secured, as at 21, to a support 22 arising from 75 the floor of the derrick. By adjusting this limiting band, the space between adjacent faces of the calf wheel and band may be at all times maintained uniform, regardless of wear to which the band 13 is subjected. 80 The connection of the brake band 13 with the crank is preferably likewise made adjustable so that any extreme slack occurring in the brake band may be removed and accordingly the necessary movement of the 85 lever 18 to apply the band kept within certain limits.

In accordance with my invention, I further provide an operating mechanism for the band including a shaft 24 mounted in 90 suitable bearings 25 and 26 arising from the floor of the derrick. Between the bearings 25 and 26 a drum 27 is secured to the shaft and at one end of the shaft a hand wheel 28 is applied thereto. Adjacent the hand 95 wheel, the shaft is formed with a ratchet 29 and the adjacent bearing 25 has pivoted thereto a dog 30 for coaction with the ratchet. This dog is connected by a link 31 with a foot treadle 32, the connections 100 and construction of the various parts being such that the dog normally assumes an inoperative position but may be engaged with the ratchet by application of pressure to the foot treadle. A cable or the like is wound several times about the drum and is trained about a pulley or pulleys 33 and between the ends of the cable is inserted a sleeve 34 which 105 slidably embraces the lever 18 intermediate the ends thereof and adjacent its free end.

In the use of the device, when it is desired to apply the brake, the hand wheel is rotated

to the left. This forces the lever 18 downwardly through the sleeve 34 in the direction of the arrow with the result that the brake band is tightened upon the periphery of the calf wheel. When the brake band has been tightened, the pawl may be engaged with the ratchet by placing the foot upon the foot treadle and after the pawl is engaged, the tendency of the brake to release will keep a constant strain of the ratchet teeth against the pawl so that this engagement is maintained. Any tendency of the lever to kick will be frustrated by the engagement of the sleeve therewith and the operator is enabled to leave the lever to assist in other work about the derrick. When it is desired to release the lever, the wheel is rotated in a direction to tighten the same for a sufficient distance to release the pawl which moves to its inoperative position, thus permitting the wheel to be reversed and the brake to be released.

It will, of course, be obvious that the construction hereinbefore set forth is capable of a certain range of change and modification without materially departing from the spirit of the invention and I accordingly do not limit myself to such specific structure except as hereinafter claimed.

30 I claim:—

1. In combination, a calf wheel brake band and an operating lever for shifting the same, a drum, a cable wound upon the drum and trained through a suitable pulley, a sleeve with opposite sides of which the ends of the cable connect, said sleeve slidably embracing the lever and means for locking the drum against rotation in a direction permitting movement of the lever to release 40 the band.

2. In combination, a calf wheel brake band and an operating lever for shifting the same, a drum, a cable wound upon the drum and trained through a suitable pulley, a sleeve with which the ends of the cable connect slidably embracing the lever and means for locking the drum against rotation in a direction permitting movement of the lever to release the band, said means being nor-

mally inoperative and upon a predetermined 50 operation of the drum releasing the drum to permit rotation thereof in a direction releasing the lever.

3. In combination, a calf wheel brake band and an operating lever for shifting the same, a drum, a cable wound upon the drum and trained through a suitable pulley, a sleeve with which the ends of the cable connect slidably embracing the lever, a ratchet associated with the drum, a normally inoperative pawl for engaging the ratchet to prevent rotation of the drum in a direction permitting movement of the lever to release the band and means for shifting said pawl into engagement with the ratchet. 65

4. In combination, a calf wheel, a brake band therefor and an operating lever for shifting the brake band, a drum, a cable wound upon the drum connections between opposite ends of the cable and opposite sides 70 of the operating lever for shifting the operating lever in opposite directions and means for rotating the drum.

5. In combination, a calf wheel, a brake band therefor and an operating lever for 75 shifting the brake band, a drum, a cable wound upon the drum, connections between opposite ends of the cable and opposite sides of the operating lever for shifting the operating lever in opposite directions and 80 means for locking the drum against rotation in a direction permitting movement of the lever to release the band.

6. In combination, a calf wheel, a brake band therefor, an operating lever for the 85 brake band swinging in a given plane, a sleeve slidably engaging the lever, means connected with the sleeve for positively shifting the sleeve in opposite directions to thereby operate the brake lever, said means including a rotatable operator actuated element remote from the plane of swing of the lever and means for locking the first named means against movement in one direction. 90

In testimony whereof I hereunto affix 95 my signature.

J CLIFFORD SMITH.
